UNITED STATES PATENT OFFICE.

JAMES T. A. TODD, OF FORT WORTH, TEXAS.

BALE-TIE-SECURING DEVICE.

1,217,851.

Specification of Letters Patent. Patented Feb. 27, 1917.

Application filed October 26, 1916. Serial No. 127,890.

To all whom it may concern:

Be it known that I, JAMES T. A. TODD, a citizen of the United States, residing at Fort Worth, in the county of Tarrant and 5 State of Texas, have invented certain new and useful Improvements in Bale-Tie-Securing Devices, of which the following is a specification.

My invention relates to devices for placing ties on bales of fibrous material, and more particularly on bales of cotton, and the object is to provide simple devices by which bale-ties can be easily and quickly put on bales of cotton. This device is particularly designed for replacing ties which have been broken from the bales. The practice now in putting on ties, where buckles have been broken, is to put the bale back in the compress and then compress the bale 20 so that the ties can be placed on as in the first instance of compressing the bale. With such device as is set forth herein, the ties can be put on the bale without the expense and time of putting the bale back into the 25 compress. Other objects and advantages will be fully explained in the following description, and the invention will be more particularly pointed out in the claims.

Reference is had to the accompanying 30 drawings which form a part of this application, in which—

Figure 1 is a plan view of the device.

Fig. 2 is a plan view of the frame.

Fig. 3 is an elevation of the wide end of 35 the gripping block.

Fig. 4 is a bottom plan view of the same.

Fig. 5 is an elevation of the narrow end of the gripping block.

Fig. 6 is a top plan view of the clamps.

40 Fig. 7 is an elevation of the wide end of said clamps; and

Fig. 8 is a bottom plan view of the same.

Fig. 9 is an elevation of the narrow end of the clamps.

45 Fig. 10 is an end view of the screw shaft socket.

Fig. 11 is a side view of the same.

Fig. 12 is a side elevation of the device assembled, showing portions of the end of a 50 tie.

Fig. 13 is an enlarged side elevation of the power screw.

Fig. 14 is an elevation of the rear end of the stationary gripping block.

55 Similar characters of reference are used

to indicate the same parts throughout the several views.

The present application is filed to take the place of the application filed by me on August 28, 1916, Ser. No. 117,327.

A frame 1, flat and substantially quadrangular in form, is provided at one end with the lug 2 which may be formed integral therewith, and the frame has an elevated portion for the purpose of locating the lug 2. A stationary gripping block 3 is mounted on the lug 2 and clamps 5 are received in a recess 4 in the underside of the block 3. The tie 6 is caught between the clamps 5. The clamps 5 are angular and have T-shaped ribs 14 on the upper side which are received in grooves 25 in block 3. A stationary gripping block is necessary at one end of the frame 1 to hold the end of the tie 6, which carries the bale-tie buckle 7. 75 A movable gripping block 8 is also necessary to bring the other end of the bale-tie in position to be caught on the buckle 7. The blocks 3 and 8 are similar in gripping structure and similar reference numerals are used 80 to designate like parts of each. The block 3 has a raised socket portion 9 which has socket 11 to receive the lug 2. The block 8 has a raised portion 10 with a socket 11, which should be in line with the lug 2. The 85 raised portion 10 may be formed integral with the block 8 and the raised portion 9 may be formed integral with the block 3. The block 8 has a groove 4 and grooves 25 therein to receive clamps 12 with their ribs 14 and the clamps 12 grip the end 13 of the tie which is to be forced near enough to be caught in the bale-tie buckle 7. The tie is gripped by the clamps 12, and the clamps 12 are caught and wedged into the converging 90 grooves in the block 8, which grooves are wider at the front end than at their rear end so that the harder the push on the tie the tighter will the tie be gripped. The clamps 12 are angular and have rib portions 14 100 lying in the grooves 25.

The clamps 5 and 12 are recessed at their adjacent edges on the under side to receive the ends of the tie 6 and 13. The tie rests against flanges 26 by which the tie is prevented from falling out of the clamps. The recesses in the bottom parts of the clamps 5 and 12 are curved on the upper sides of the recesses so that when strain comes on the edges of the tie the tie will buckle or curve 110

upwardly toward the center of the tie. This is necessary because otherwise the tie might buckle downward and thus slip out of the clamps.

5 Means are provided for forcing the tie end 13 toward the tie end 6 so that the two ends can be caught in the buckle 7. A screw socket 15 is hung on the frame 1 by means of a headed bolt or lug 16 which is rigid 10 with the socket 15 and is adapted to lie in a recess 17 in the frame 1. This recess is curved so that the lug 16 can rock therein. The socket 15 is firmly secured to the frame 1 by a stud bolt 18 which passes through an 15 angular recess 19 in the frame 1. A power screw-shaft 20 is threaded and operates through the socket 15, which is threaded, and the screw-thread has a pintle or stem 21 which enters the recess 11 in the block 8. 20 The shoulder 22 will bear against the end of the block 8 and will force the block 8 toward the block 3, when the screw-shaft is driven, and thus bring the end 13 of the tie near enough to the end 6 to be caught in the buckle 7. In order that the tie may be shifted 25 laterally at the end so that it can enter the buckle (which will be turned on the side to receive the tie), the angular socket 19 will permit the swinging of the socket 15 on the lug 16, which will turn in the recess 17, and the bolt 18 will pass outwardly and upwardly in the slot 19. The ties are prepared 30 for receiving the buckle by bending the ends of the tie inwardly; that is, so that the folded ends 23 will be next to the bale. It is apparent from Figs. 4 and 6 that the converging grooves in the blocks 3 and 8, and the angular clamps 5 and 12, will grip the ties so that the ends will be brought together 35 to receive the buckle when the block 8 is driven by the screw-shaft 20. The clamps are released by unscrewing the screw-shaft 20.

The socket 15 should be constructed with 45 the side next to the frame 1 flat for making the screw-shaft steady against lateral turning motion while driving the gripping block 8. Various changes in the sizes and proportions and construction of the various parts 50 may be made without departing from my invention.

Means are provided for preventing the clamps 5 and 12 from falling from the gripping blocks 3 and 8. Portions of the outer 55 flanges of the T-ribs 14 are cut away, as at 27, and set screws 28 are inserted in the outer sides of the gripping blocks and project into the cut-outs 27. The cut-outs 27 should be long enough to permit sufficient 60 movement of the clamps 5 and 12 to perform their functions of clamping and releasing the ends of the ties.

I claim:

1. A bale-tie securing device comprising 65 a frame, a stationary gripping-block mount-

ed on one end of said frame, and a movable gripping-block mounted on the other end of said frame, and said blocks having each a groove therein and said grooves converging in opposite directions, clamps in said grooves 70 provided with recesses for gripping the ends of the tie, and means for forcing said movable block toward said stationary block for bringing the ends of the bale-tie together.

2. A bale-tie securing device comprising 75 a frame, converging clamps stationary on one end of said frame and converging clamps movably mounted on the other end of said frame, said clamps having recesses for gripping the ends of a bale-tie, and one side of 80 each recess being curved for permitting the ties to buckle inwardly and not outwardly relative to the clamps, and means for driving said movable clamps toward said stationary clamp for bringing the ends of the 85 bale-tie together.

3. A bale-tie securing device comprising a frame, angular converging clamps stationary on one end of said frame and angular converging clamps movably mounted on 90 the other end of said frame, said clamps having curved recesses to grip and hold the ends of a bale-tie, and means swingingly mounted on said frame for forcing said movable clamps toward said stationary clamps for 95 bringing the ends of the bale-tie toward each other.

4. A bale-tie securing device comprising a frame, a stationary gripping-block mounted on one end of said frame and a movable 100 gripping-block mounted on the other end of said frame, said blocks having oppositely converging grooves therein, clamps in said grooves provided with recesses to receive the ends of the tie, a screw-shaft socket mounted 105 on said frame, and a screw-shaft operating through said socket for driving said movable block toward said stationary block.

5. A bale-tie securing device comprising 110 a frame, a stationary gripping block mounted on one end of said frame, and a movable gripping block mounted on the other end of said frame, said blocks having oppositely extending converging grooves and T-shaped grooves within said converging grooves, 115 clamps mounted in said grooves for engaging the ends of the tie and having T-shaped ribs on the upper side to enter said T-shaped grooves, a screw-shaft socket swingingly mounted on said frame, and a screw-shaft 120 operating through said socket and engaging said movable block for driving said block toward said stationary block for bringing the ends of the tie together.

6. A bale-tie securing device comprising 125 a frame provided with an inwardly projecting lug at one end, a stationary gripping block having a recess therein mounted on said lug, and a movable gripping block provided with an opening therethrough mount- 130

ed on the other end of said frame, said blocks having oppositely converging grooves therein, clamps for engaging the bale-tie mounted in said grooves, a power screw-shaft socket 5 swingingly mounted on said frame, and a power screw-shaft operating through said socket and having a pintle projecting in the opening of said movable block.

7. A bale-tie securing device comprising 10 a frame, a stationary gripping block mounted on one end of said frame and a movable gripping block mounted on the other end of said frame, each block having a longitudinal

groove therein and the grooves converging in opposite directions, clamps in said grooves 15 for gripping the ends of the ties and having recesses in the sides thereof, set screws for projecting through the sides of said gripping block in said recesses, and means for forcing said movable block toward said stationary block for bringing the ends of the bale-tie together.

In testimony whereof, I set my hand, this 13th day of October, 1916.

JAMES T. A. TODD.
